Primary Examiner — Patricia Palasik*(74) Attorney, Agent, or Firm* — Douglas B. Farrow(57) **CLAIM**

The ornamental design for a plural component proportioner, as shown and described.

DESCRIPTION

FIG. 1 is a front right isometric view of a plural component proportioner;

FIG. 2 is a front left isometric view thereof;

FIG. 3 is a front view thereof;

FIG. 4 is a right side view thereof;

FIG. 5 is a left side view thereof;

FIG. 6 is a rear view thereof;

FIG. 7 is a top view thereof; and,

FIG. 8 is a bottom view of a plural component proportioner. The broken lines in the drawings depict unclaimed environmental subject matter.
